UNITED STATES PATENT OFFICE.

REUBEN B. BENJAMIN, OF CHICAGO, ILLINOIS, ASSIGNOR TO BENJAMIN ELECTRIC MANUFACTURING COMPANY, OF CHICAGO, ILLINOIS, A CORPORATION OF ILLINOIS.

REFLECTOR-SHADE.

1,103,252.

Specification of Letters Patent. Patented July 14, 1914.

Application filed August 23, 1910. Serial No. 578,480.

To all whom it may concern:

Be it known that I, REUBEN B. BENJAMIN, a citizen of the United States, residing at Chicago, in the county of Cook and State 5 of Illinois, have invented new and useful Improvements in Reflector-Shades, of which the following is a full, clear, concise, and exact description, reference being had to the accompanying drawing, forming a part of 10 this specification.

My invention pertains to reflector shades and particularly to such reflector shades as are used for street lighting.

It is the object of my invention to provide 15 a reflector shade which will distribute to the best advantage the light shed by the lamp with which it is used.

In the lighting of streets by means of lamps hung in the center of the road it is 20 desirable to project the light as far forward and backward along the road as is possible but it is unnecessary to project the light to a greater distance sidewise than is sufficient to light the sidewalks. In order 25 that the light shed by each lamp may be distributed to the greatest advantage, it is desirable, therefore, that it be projected to a considerably greater distance frontward and backward along the roadway than side- 30 wise. In the lighting of the intersection of two streets by means of a lamp placed in the center of the road, it is desirable to project the light as far as possible down each road but it is unnecessary to project it to 35 any very great distance toward the street corners, a distance sufficient to light the sidewalks at the corners being sufficient. With the above conditions in view I have 40 devised a reflector shade by means of which the light shed by the lamp in connection with which it is used is distributed to greater advantage than has hitherto been possible.

In order that my invention may be fully 45 understood I have shown a reflector shade constructed in accordance therewith, in the accompanying drawings; in which:

Figure 1 is a perspective view of the shade secured to a lamp socket and having a lamp 50 in place therein; Fig. 2 is a plan; and Fig. 3 is a partly sectional elevation of the shade.

The form of shade which I have shown 55 in the drawings is of a kind adapted for use in the lighting of an intersection of two streets, the shade being attached to a lamp

socket hung in the middle of the roadway. The shade shown in the drawings is constructed of sheet metal suitably enameled, and consists of a frusto-conical portion 10 which incloses the upper part of the lamp 60 and is provided with an inwardly extending flange by means of which it may be secured to the lower part of the lamp socket, the latter being indicated as 12 in Fig. 1 of the drawings. The metal of the shade is bent 65 to form four radially extending reflectors, the upper portions 13 of which are in the form of truncated hollow semi-paraboloids, while the lower portions 13^a are in the form of walls extending downwardly and outwardly from the edges of the paraboloidal portions 13. The reflectors are symmetrical and a description of one of them, therefore, will suffice. One of the reflectors is shown in section at the right hand side of Fig. 3, 70 the axis of the paraboloidal portion 13 thereof being indicated as A B. The parabolic longitudinal curve of the portion 13 is indicated as B C. It will be seen that the portion 13 is so disposed that its axis A B 75 passes through the axis of the shade and will therefore pass through the filament of a lamp carried in the socket 12. The portion 13 is so disposed that the axis A B is inclined downwardly and outwardly and 80 passes through the filament at a point adjacent the center thereof, the focus F of the paraboloid being situated in the line of the filament, preferably adjacent the center of the latter. The walls 13^a extending downwardly and slightly outwardly from the lower edges of the portions 13 are bent horizontally in parabolic curves; they serve to 85 project outwardly the light emanating from the part of the filament below the focal point of the paraboloidal portions 13. These downwardly extending walls 13^a are of some importance owing to the length of filament usually used in incandescent lamps. Lamps of this character project much more 90 light in a horizontal plane than vertically. The flat portions 13^a of the reflectors are cut off in a plane forming an extremely flat cone, the adjacent edges being connected by flat portions 14, which portions therefore 95 also form parts of a flat cone.

In use, the reflector shade is so arranged upon the socket that the reflectors will point up and down the roads at the intersections. By this means light will be cast a consider- 100 105 110

able distance up and down the roads, but only enough light will be projected outward between the reflectors 13 to light the sidewalks at the corners of the streets, such light 5 being reflected downward by the flat portions 14. It will thus be seen that the shade according to my invention distributes the light to a very much better advantage than is done by the ordinary flat shade, the light 10 wasted being reduced to a minimum.

What I claim as new, and desire to secure by Letters Patent, is:

A reflector shade comprising a plurality of radially extending portions curved sub-

stantially into the form of partial paraboloids, the axes of which are inclined slightly downward, walls extending downwardly from said portions and curved into the form of parabolas, and a plurality of portions disposed between said curved portions, 15 and forming parts of a flat conical reflector.

In witness whereof, I have hereunto subscribed my name in the presence of two witnesses.

REUBEN B. BENJAMIN.
